SHELF FOR GAS OVENS

Charles R. Spine and Leonardo Calaluca,
Somerville, N. J.

Application May 27, 1935, Serial No. 23,791

6 Claims. (Cl. 126—337)

Our invention relates, generally, to ovens and more particularly to improvements in shelves for ovens of gas ranges.

In the usual gas ranges of commerce, the heat rises too rapidly to the top of the oven. This condition results in the uneven cooking of food on the oven shelves, particularly at the top and bottom, and too rapid dissipation of the heat through the top of the oven and the usual vent in said top.

With the foregoing in mind the principle object of our invention is to provide means for retarding the rise of the heat in the oven during the process of cooking, particularly below the food being cooked therein, and distributing the heat uniformly beneath the food whereby the latter is cooked evenly throughout the same.

Specifically stated the primary object of our invention is to provide a simply constructed shelf adapted for use in the ovens of ranges of standard construction and equipped to effect a retarded rise of the heat from the lower part of the oven to the upper part and particularly designed to distribute the heat laterally beneath the food being cooked.

Another object is to provide an oven shelf, for the purposes above set forth, and which is adjustable as to length and width to compensate for manufacturing irregularities in the oven.

Still another object is to provide a device of the character specified which is strong and durable, light in weight and economical to manufacture.

Other objects, together with the nature of our improvements and their advantages, will be readily understood when the following description and claims are read with reference to the accompanying drawings.

In said drawings:

Figure 1 is a fragmentary view in vertical transverse section of a gas range equipped according to our invention.

Fig. 2 is a similar view in vertical section taken on the line 2—2 of Fig. 1 looking in the direction indicated by the arrows.

Fig. 3 is a view in horizontal section taken on the line 3—3 of Fig. 2 looking in the direction indicated by the arrows.

Fig. 4 is a view in horizontal section of the oven shelf detached, parts showing in elevation.

Fig. 5 is a fragmentary view in perspective of shelf supporting guides, a heat conducting flue with which the usual gas ovens are equipped, and a closure member for said flue.

Fig. 6 is a fragmentary sectional view taken on the line 6—6 of Fig. 4 looking in the direction

indicated by the arrows, and drawn to an enlarged scale.

Fig. 7 is a similar view taken on the line 7—7 of Fig. 4 looking in the direction indicated by the arrows.

Fig. 8 is a fragmentary view in top plan of the rear edge of the shelf.

Fig. 9 is a similar view of an adjustable ledge plate for the rear edge of the shelf.

Fig. 10 is a fragmentary perspective view of the parts of the oven shelf disassembled.

Fig. 11 is a fragmentary perspective view of one front corner of the shelf and an adjustable ledge member associated with the front edge of the shelf.

Fig. 12 is a view in transverse section of a modification of the invention, and

Fig. 13 is a view in vertical section taken on the line 13—13 of Fig. 12 looking in the direction indicated by the arrows.

Referring to the drawings and first to the preferred embodiment of our invention illustrated in Figs. 1 to 11, the numeral 1 designates a portion of a gas range of commerce, 2 the burners thereof and 3 the usual oven equipped with a door 4. The oven 3 is of the usual type embodying inner side, rear and top walls 5, 6 and 7, respectively, spaced from the exterior walls 8 of the oven to form a heat conducting chamber 9 surrounding said side, rear and top walls and communicating with a combustion chamber 10 below the bottom walls 11. The side walls 5 have formed therein the usual vertically extending flue portions 12 opening into the oven, and the top and bottom walls 7 and 11 are provided with the usual apertures, 13 in the top wall, and 14 in the bottom wall, for the passage of heat through the interior of the oven. The numeral 15 designates the baffle plates at the top of the oven having a purpose well understood and 16 the outlet vent pipe communicating with the chamber 9. On the inside of the walls 5 are the usual opposed, fluted guiding and supporting plates 17 for the shelves of the oven and which extend across the flue portions 12 to form the inner side thereof.

The shelf 18 of our invention comprises upper and lower plates 19 and 20, respectively, preferably formed of sheet metal and secured together at their edges, in a manner presently explained, to form therebetween a shallow heat distributing chamber 21 in said shelf. The upper plate 19 at its rear and side edges is bent to form vertical rear and side walls 22 and 23, respectively, for the shelf terminating in laterally extending rear

and side flanges 24 and 25, respectively, surrounding the rear and side edges of said shelf and to which the lower plate 20 is secured by bending the rear and side edges 26 and 27, respectively, 5 thereof upwardly over said flanges 24 and 25. The front edge of the upper plate 19 is bent downwardly to form a vertical front wall 28 for said shelf extending below the plate 20 to provide a hand grip portion 29 across the front edge of said 10 shelf for manipulating the latter and which is crimped at its lower edge rearwardly and upwardly around a depending flange 30 on the front edge of said plate 20. Screws 31, provided with nuts 32, passing through the described rear and 15 side edges of the shelf 18 clamp the said edges together.

At its side edges the shelf 18 is provided with laterally adjustable ledges 33, respectively, in the form of transversely U-shaped strips of sheet metal 20 fitting over and under the bent edges 27 and provided with slots 34 for receiving the screws 31 so as to be clamped in position by said screws. The front ends of the ledges 33 are provided with right angularly related end portions 35 for overlapping the ends of the hand grip portion 29 to form lateral extensions of the same when said ledges are adjusted outwardly. At its rear edge the shelf 18 is provided with a similar laterally adjustable ledge 36 having slots 37 therein for 25 receiving the screws 32 at the rear of the shelf and adjustably clamped thereby to the rear edge of the bottom wall 20. The ends of the ledge 36 are received in the rear ends of the ledges 33, as shown in Fig. 4, to prevent said ends of the ledge 30 36 from being bent downwardly.

Within the chamber 21 of the shelf 18 and extending centrally of said chamber from the rear wall 22 to a suitable point adjacent the wall 28 is a substantially rectangular baffle member 37', open at its front and bottom, and comprising laterally spaced walls 38 terminating at their 40 front ends in rearwardly inclining end portions 39 and having lateral flanges 40 by means of which said member is secured as by rivets 41 to the plate 20. The member 37' is preferably provided with a top plate 42 supporting the plate 19 to reinforce the latter. The bottom plate 18 is provided with a plurality of aligned apertures 43 communicating with the space within the baffle member 37'. The rear wall 22 is provided with a 45 plurality of apertures 44 upon opposite sides of said baffle member.

The described shelf 18 is designed to be mounted on the plates 17 with the ledges 33 supported by said plates and with the ledge 36 engaging the rear wall 22 and the front wall 28 in position to be engaged by the door 4 so that said shelf forms a transverse partition within the oven fitting snugly therein. By adjusting the ledges 33 and 50 36 the width and length of said shelf may be varied to obtain such a snug fit, as will be clear, it being understood, of course, that the shelf is built in the approximate width and length of the interior of the oven.

The heat rising beneath the shelf 18 is retarded 55 and in effect concentrated immediately below said shelf. The heat entering the chamber 21 through the apertures 43 is directed by the walls 38 of the baffle member 37' out of the open end of the latter against the front wall 28 of said 60 shelf and around the sides of the chamber 21, by the inclined portions 39 to find outlets through the apertures 44 in the rear wall 22 of said shelf. As will be manifest the described deflection of the 65 heat in the chamber 21 provides for a retarded 70 flow of the same into said chamber and for uni-

formly distributing the heat in the chamber immediately below the top wall 19 of the shelf.

If desired the flue portions 12 of the side walls 5 may be closed, either at the top or bottom thereof, by means of closure plates 45 adapted to fit into 5 said portions and provided with inner edges 46 bent upon themselves into clip form to clip over either the upper or lower edges of said plates 17.

In Figs. 12 and 13 a modified form of means 10 has been shown for variably supporting the shelf 18 in an oven, not equipped with supporting plates 17, and comprising the following. A shaft 47 is journaled in the upper part of the oven 3 centrally thereof for endwise movement in brackets 48 suitably secured to the top wall 7 of 15 the oven 3. Adjacent each end of the shaft and fast thereon is a pair of sheaves 49. Each pair of sheaves has oppositely wound thereon a pair of chains 50 trained through eyelets 51 in the sides of the oven and secured to the edges of the 20 shelf, as at 52, so that said shelf may be raised and lowered by rotation of the shaft 47 in opposite directions respectively. The shaft 47 is equipped with a hand wheel 53 fast on one end thereof for rotating and sliding said shaft in the 25 brackets 48. An angular stop 54 is provided on the shaft 47 for engagement with one of the brackets 48 to hold the shaft 47 against rotation under the weight of the shelf 18, said stop being engageable and disengageable from said bracket 30 by endwise movement of the shaft.

The foregoing constitutes a detailed description 35 of our invention and it is thought that its operation and advantages will be clear therefrom.

It is to be understood however that the invention is susceptible of modification other than that disclosed without departing from the spirit of the invention and that right is herein reserved to such other modifications falling fairly within the 40 scope of the claims appended hereto.

What we claim is:

1. A shelf for ovens comprising, top and bottom plates, respectively, connected together at their edges in spaced apart relation to form a 45 heating chamber therebetween having side and end walls, respectively, a baffle member in said chamber extending centrally thereof from one wall toward the opposite wall and including spaced apart side walls forming a flue therebetween having a closed end and an open end, the bottom plate of said shelf having apertures 50 therein communicating with said flue, and the first mentioned wall of said chamber being apertured upon opposite sides of said member for the passage of heat from said chamber.

2. A shelf for ovens comprising, top and bottom plates, respectively, connected together at their edges in spaced apart relation to form a heating chamber therebetween having side and end walls, respectively, a baffle member extending 60 forwardly in said chamber centrally thereof and from the rear wall and including spaced apart side walls forming a flue therebetween having a closed rear end and opening onto the front wall, the bottom plate of said shelf having apertures therein communicating with said flue for the passage of heat into said chamber through said flue, and the first mentioned wall of said chamber being apertured upon opposite 65 sides of said member for the passage of heat from said chamber, the walls of said flue at the open end of the latter having laterally and rearwardly inclining heat deflecting portions.

3. A shelf for transversely partitioning an oven and comprising, top and bottom plates, re- 70

spectively, secured together at their edges in spaced apart relation to form therebetween a heating chamber having front, rear and side walls, respectively, a baffle member extending 5 part way across said chamber centrally thereof and from said rear wall and including spaced apart side plates forming a flue therebetween having a closed rear end and opening onto the front wall of the chamber, the bottom plate of 10 said shelf having apertures therein communicating with said flue for the passage of heat into said chamber through said flue, exit openings in the rear wall of the shelf for the passage of heat out of said chamber, said shelf being 15 provided with a rearwardly extending ledge below said last apertures for spacing said rear wall from the rear of the oven to permit heat from said chamber to pass above said shelf.

4. A shelf for transversely partitioning an 20 oven and comprising, top and bottom plates, respectively, secured together at their edges in spaced apart relation to form therebetween a heating chamber having front, rear and side walls, respectively, a baffle member extending 25 part way across said chamber centrally thereof and from said rear wall and including spaced apart side walls forming a flue therebetween opening onto the front wall of the chamber, the bottom plate of said shelf having apertures there- 30 in communicating with said flue for the passage of heat into said chamber through said flue, the rear wall of the chamber being apertured upon opposite sides of the flue for the passage of heat out of said chamber, said shelf being provided 35 with a rearwardly extending ledge below said last apertures for spacing said rear wall from the rear of the oven to permit heat from said chamber to pass above said shelf, and the side walls of said member at the open end of the

flue being provided with outwardly and rearwardly inclined portions for deflecting heat from said flue laterally and rearwardly in said chamber.

5. A shelf for ovens comprising top and bottom plates connected together adjacent their 5 edges in spaced apart relation to form a heating chamber therebetween having front, side, and rear walls, respectively, a baffle member extending forwardly in said chamber centrally thereof from said rear wall and comprising a 10 top part supporting the top plate of the chamber, and spaced apart side walls forming a flue therebetween terminating short of the front wall of the chamber and in opposed flanges inclined outwardly and rearwardly of said flue and of 15 the same height as said chamber, the rear edge of the shelf being provided with a flange for spacing the rear wall of the shelf from the inside wall of the oven, and said rear wall of the shelf having apertures formed therein upon opposite sides of the baffle member respectively.

6. A shelf for use in an oven comprising a pair of spaced apart plates connected together adjacent their edges to form a heating chamber therebetween and having a hand grip portion 25 extending across the front edge of the shelf and depending below the same, a baffle member disposed within said chamber, and a ledge member disposed at each side of said plates and adapted to be adjusted laterally with respect thereto, each 30 of said ledge members having a projecting flange extending along its front edge outwardly of said grip portion, the grip portion being disposed in snug engagement with the intermediate portion of the oven door and said depending flanges on 35 the ledge members snugly engaging the marginal edge portions of the oven door when it is closed.

CHARLES R. SPINE.
LEONARDO CALALUCA.
